UNITED STATES PATENT OFFICE

2,418,712

ALTITUDE COMPENSATED INTERNAL-
COMBUSTION AIR HEATERSeymour E. Heymann, Chicago, Ill., assignor to
Stewart-Warner Corporation, Chicago, Ill., a
corporation of Virginia

Application March 1, 1943, Serial No. 477,523

14 Claims. (Cl. 126—116)

1
My invention pertains to altitude compensated heaters and more particularly to the means for maintaining the richness of the combustible mixture uniform under all variations in altitude.

Where heaters of the internal combustion type are provided with the usual carburetor, the richness of the mixture supplied to the combustion chamber of the heater increases with increases in altitude. This is objectionable and an object of my invention is to provide a heater having new and improved means for producing a combustible mixture which will be of uniform richness at all altitudes.

Another object of my invention is to provide a heater having means for supplying fuel to the combustion chamber and operating on the difference in pressure between the combustion chamber and the induction tube leading thereto.

Another object of my invention is to provide an internal combustion type of heater having fuel supply means operating on the difference in pressure between the combustion chamber and the induction tube leading thereto and wherein novel means is provided for maintaining this difference in pressure constant at all altitudes.

Another object of my invention is to provide an altitude compensated heater having a minimum number of operating parts and requiring a minimum of service or other attention.

Another object of my invention is to provide an altitude compensated heater which has a high heat output per unit of weight and which is particularly adapted for use in aircraft.

Other objects and advantages will become apparent as the description proceeds.

In the drawings:

Fig. 1 is a longitudinal section through an altitude compensating heater embodying one form of my invention;

Fig. 2 is a partial view similar to Fig. 1, but showing a modified form of my invention;

Fig. 3 is a view showing a transverse section taken on the lines 3—3 of Fig. 2; and

Fig. 4 is a partial view similar to Fig. 1, but showing a further modification.

In Fig. 1, I have illustrated an internal combustion type of heater having a combustion chamber 10, which is supplied with fuel through the slots 12 in a burner tube 14. The slots 12, if so desired, may be arranged to give the combustible mixture a whirling motion as it enters the combustion chamber 10. This mixture is initially ignited by an electrical igniter 16 supplied with current from any suitable source, and preferably thermostatically controlled, so that the igniter 16 is disconnected from its source of electrical energy

when the heater attains normal operating temperature. A re-igniter 18 is provided to insure maintenance of combustion after the igniter 16 has been disconnected from its source of current.

The curved plate 20 connects the combustion chamber 10 to one end of a heat exchanger 22 of tubular conformation and having hollow fins 24 extending lengthwise thereof. The ends of the hollow fins are sealed, as indicated at 26 and 28, so that the hot products of combustion created in the combustion chamber flow into the hollow fins and lengthwise thereof.

As these products of combustion traverse the hollow fins, heat is given up to these fins and the cooled products of combustion pass from the hollow fins into an outlet chamber 30. This chamber is provided with an outlet fitting 32, which affords communication between the chamber and any suitable exhaust pipe (not shown) which may be attached to the threaded end 34 of the fitting 32.

A muffler 36 is located in the heat exchanger 22 and comprises a sheet metal shell 38 containing a sound absorbing material 40, such as glass wool or stainless steel wool. The shell 38 is provided with openings 42 which constitute acoustic couplings permitting the sound to pass into the interior of the muffler shell. The forward end of the muffler is tapered, as indicated at 44, to direct the hot products of combustion into the hollow fins 24. This tapered end terminates in a cap or nose 46 which is spaced from the end wall of the muffler shell to provide an acoustic chamber 48, which is connected to the interior of the muffler shell by openings 50.

The heater is enclosed in a casing 52 which surrounds the heat exchanger 22 and cooperates therewith to form a path for ventilating air. As this air traverses the spaces between the hollow fins 24, it absorbs heat from the heat exchanger 22. The heated ventilating air is discharged from the lefthand end of the casing 52 into a cabin or other space to be heated, or into a duct system having a plurality of outlets at selected locations.

The casing 52 is supplied with ventilating air through a ventilating air inlet 54 which is connected to the righthand end of the casing 52 by a sheet metal cone 56. The inlet 54 may be connected to any suitable ram or blower, or other source of air supply. This source may also supply air to the combustion air inlet 58, or, if preferred, each inlet may have its own independent source of air.

The pipe which is illustrated as forming the combustion air inlet 58 is attached to a nipple

60 carried by the housing 62 attached to one end of the combustion chamber 10 and supported by a spider-like frame 64 which centers these parts relative to the righthand end of the casing 52. The induction pipe or air inlet 58 is in communication with the burner tube 12 by way of nipple 60 and an expandable conduit 66 which connects the righthand end of the burner tube with the nipple 60. The burner tube 14 is slidably mounted in a hollow screw 68 and this burner tube and the other mechanism associated with the housing 62 constitutes an altitude compensating mechanism as is hereinafter described.

10 Fuel is supplied to the induction tube 58 by a pressure multiplying mechanism 70, which is responsive to differences in the pressure between the induction tube 58 and the combustion chamber 10. This mechanism 70 is supplied with fuel from a pump, elevated tank, or any other suitable source through a pipe 72 which discharges into a 15 chamber 74. Communication between the chamber 74 and pipe 72 is regulated by a valve 76. The chamber 74 has a part formed by an expandable and contractable bellows 78, whose righthand end rests against a sheet metal cup 80 20 which moves in response to differences in pressure on opposite sides thereof to provide expansion and contraction of the bellows 78, and valve 76 opens and closes in response to such expansion and contraction of the bellows 78.

25 A second bellows 82 connects the flange 84 of cup 80 with a rigid head 86, forming part of the casing of the pressure multiplying means 70. The bellows 82, cup 80 and head 86 form a variable chamber 88 communicating with the air inlet 58 by way of pipe 90 so that the pressure in the chamber 88 varies with variations in pressure in the air inlet or induction pipe 58. A third chamber 92 in the pressure multiplying means 70 communicates with the combustion chamber 10 by way of pipe 94 so that the pressure in the chamber 92 varies with the pressure in the combustion chamber 10. The cup 80 is exposed to the differential pressure between chambers 88 and 30 92 and exerts a force on the bellows 78 proportional to this pressure difference. Since the effective area of the cup 80 is much greater than the cross-section of the bellows 78, the force available to open the valve and permit fuel to flow from chamber 74 through pipe 95 to fuel jet 96 35 is much greater than the difference in pressure across the burner head, that is, between the air inlet 58 and the combustion chamber 10.

40 In internal combustion heaters in which the burner tube 14 is fixed, the pressure differential between the air inlet and combustion chamber increases with increase in the altitude at which the airplane is traveling. This means that the pressure available in chamber 74 to supply fuel to the fuel jet 96 would also increase with altitude, with the undesirable result that the richness of the combustible mixture flowing to the combustion chamber would also increase with increase in altitude. An important feature of my invention lies in the provision of means whereby the pressure drop across the burner head is maintained constant for all altitudes.

45 The casing 62 and its associated mechanism operates on the principle of an aneroid barometer and serves to shift the burner tube 14 with changes in altitude to uncover more or less of the slots 12 through which the combustible mixture passes into the combustion chamber. By uncovering more of these slots as the altitude of the 50 55 60 65 70 75 80 85 90 95 100

plane increases, the pressure drop across the burner head is prevented from increasing and the richness of the combustible mixture supplied to the combustion chamber is likewise prevented from increasing. This barometric control also has the further advantage of reducing the resistance to flow through the heater and permits the heater to operate at full capacity at high altitudes.

The burner tube 14 has a radially projecting flange 98 connected by a bellows 100 to wall 102 of the casing 62 to form a chamber 104 which freely communicates with the interior of combustion chamber by way of the loose fit between the burner tube and the hollow screw 68, so that the pressure in chamber 104 varies with the pressure in the combustion chamber 10. A second chamber 106 is formed in the casing 62 and this chamber is evacuated so that the pressure in chamber 104 urges the burner tube to the right as viewed in Fig. 1. A spring 108 tends to resist this movement and to urge the burner tube 14 toward the left.

As the aircraft rises higher and higher, the pressures in the combustion chamber and in chamber 104 of the barometric control device decrease and spring 108 moves burner tube 14 to the left to uncover more of the slots 12 and thus prevent the pressure drop across the burner head from increasing. As the altitude of the plane decreases, the pressure in combustion chamber 10 and chamber 104 increase to cause burner tube 14 to move to the right. This reduces the free area of the slots 12 and prevents the pressure drop across the burner head from decreasing.

35 From the foregoing, it will be apparent that my altitude compensated heater provides a minimum of resistance to flow so that it is capable of maximum operation at high altitudes. My novel heater also has the advantage of a constant pressure drop at constant flow, with increases or decreases in altitude, and is particularly adapted for use in aircraft and for other uses where relatively great variations in altitude or atmospheric pressure are encountered.

40 In Figs. 2 and 3, I have shown my invention as applied to an internal combustion heater of the type in which secondary air is mixed with the hot products of combustion before they enter the heat exchanger. In these figures I have shown a modified form of heater having a combustion chamber 120 slidably mounted on the air induction pipe 122 which is supplied with combustion air by a ram, blower or other suitable source of air supply. The lefthand end of the pipe 122 constitutes a burner tube, or its equivalent, and is provided with slots 124 through which the combustible mixture enters the combustion chamber 120. More or less of these slots 124 is uncovered, depending upon the position of the combustion chamber at any particular time.

45 Fuel is supplied to the fuel jet 126 in the induction pipe 122 by the pressure multiplying means 70, which may be identical with that shown in Fig. 1. This pressure multiplying means 70 is supplied with fuel by pipe 72 and is connected with the fuel jet 126 by pipe 95'. Pipes 90' and 94' connect the pressure device 70 with the induction pipe and the combustion chamber, respectively.

50 The combustion chamber 120 is moved lengthwise of the pipe 122 by a pair of barometric control devices 128 and 130 mounted on brackets 132 and 134 attached to a cylindrical casing

136 surrounding the combustion chamber 120 and forming a conduit for secondary air to be mixed with the products of combustion flowing from the lefthand end of the combustion chamber 20. Each of said devices comprises an evacuated bellows having a spring 138 therein. The righthand end of the cylindrical casing 136 communicates with an air inlet 140 connected to a ram, blower, or other suitable source of air supply, so that the bellows 128 and 130 are exposed to variations in atmospheric pressure resulting from variations in altitude. The bellows 128 and 130 expand with decreases in atmospheric pressure to uncover more of the slots 124 and thereby prevent increases in pressure drop between the induction pipe 122 and combustion chamber 120, with increases in altitude. With decreases in altitude, the increased atmospheric pressure contracts the bellows to shift the combustion chamber 120 to the left and reduce the free area of the slots 124.

An igniter 142 is mounted on the end wall of the combustion chamber 120, as best shown in Fig. 3, and a re-igniter 144 is mounted on the lefthand end of pipe 122. The hot products of combustion formed in the combustion chamber mix with secondary air as they leave this chamber and this mixture then passes through an opening 146 and enters the righthand end of the heat exchanger 22, which may be identical with that shown in Fig. 1 and which may be provided with a similar muffler 36.

The heater is surrounded by a cylindrical casing 148 which communicates with the air inlet 140 and directs the ventilating air over the heat exchanger 22. The casing 148 corresponds to the casing 52 of the embodiment of Fig. 1.

As the combustion chamber 120 shifts to vary the free area of the slots 124, the annular orifice 150 between the lefthand end of the combustion chamber 120 and the in-turned end 152 of the cylindrical casing 136 which admits secondary air is also varied in area. In this manner the ratio between the primary and secondary air is maintained constant for all variations in altitude. In this form of my invention the pressure drop across the heater and the fuel and primary air ratio is likewise constant for all variations in altitude.

In Fig. 4, I have shown a further form of my invention comprising a heater having a combustion chamber 160 supplied with a combustible mixture through a burner tube 162. This mixture is originally ignited by an igniter 164 and a re-igniter 166 is provided to insure combustion after igniter 164 cuts out. The hot products of combustion flow from the combustion chamber 160 into the righthand end of a heat exchanger 168, containing a muffler 170. All of the foregoing parts, except the burner tube 162, may be identical with those shown in Fig. 1.

The combustion air flows through an air inlet or induction pipe 172, around a barometric control mechanism 174, and into the burner tube 162 through slots 176 in the wall thereof. A fuel jet 178 is located in the induction pipe and is connected by pipe 95" to the pressure multiplying device 70, identical with that of the previous embodiments. Pipes 90" and 94" connect this pressure multiplying device with the induction pipe 172 and the combustion chamber 160, respectively.

Communication between the induction pipe and the combustion chamber is regulated by a valve 180 having a stem 182 slidably supported in a sleeve 184 and in a wall 186 of the control

device. The sleeve 184 is held concentrically in the burner tube 162 by vanes 188 which may be shaped to give the combustible mixture a whirling motion as it enters the combustion chamber.

The righthand end of the valve stem 182 is connected to the free end of a bellows 190. The interior of this bellows communicates with the combustion chamber 160 by way of pipes 192 and 94" so that the pressure in the interior of the bellows varies with the pressure in the combustion chamber. The control device 174 includes an evacuated chamber 194, so that the pressure in the bellows tends to move this bellows and the valve connected therewith to the right and a spring 196 tends to move these parts to the left.

With increases in altitude, the reduced pressure in the combustion chamber is communicated to the interior of the bellows 190, whereupon spring 196 increases the opening of valve 180 to prevent an increase in pressure drop between the combustion chamber and induction pipe. A decrease in altitude results in an increase in pressure in the combustion chamber 160 and bellows 190 and causes an expansion of this bellows. Such expansion moves valve 180 to the right and reduces the size of the valve opening to prevent a decrease in the pressure drop across the burner head. In other words, the operation of this form of my invention is essentially the same as that of Fig. 1. The sheet metal cap 198 forming part of the barometric control device is provided solely for the purpose of minimizing disturbances to flow of the combustible mixture about this mechanism.

In each of the embodiments of my invention which are herein illustrated and described, the structure for carrying out the objects of my invention is simple, light, has a minimum of moving parts, and is capable of long and trouble-free service. While these several embodiments are illustrative of structures for carrying out my invention, it is to be understood that my invention is not limited to the particular details shown and described, but may assume numerous other forms and that the scope of my invention is defined in the following claims.

I claim:

1. An internal combustion burner for use in airplanes comprising walls forming a combustion chamber, means including an induction pipe communicating with said combustible chamber and supplying a combustible mixture thereto, and means for increasing the area of communication between said pipe and combustion chamber with increases in altitude.

2. An altitude compensated heater of the class described comprising walls forming a combustion chamber, a heat exchanger communicating with said combustion chamber, an air induction pipe communicating with said combustion chamber, fuel supply means responsive to pressure differences between said combustion chamber and induction pipe and delivering fuel to said induction pipe, and means for preventing increases in said pressure differential with increases in altitude.

3. An altitude compensated heater of the class described comprising walls forming a combustion chamber, means including an induction pipe for supplying a combustible mixture of fuel and air to said chamber, slotted means affording communication between said pipe and chamber, and means for increasing the free area of said slotted means in accordance with increases in altitude.

4. An altitude compensated heater comprising

walls forming a combustion chamber, means including an induction pipe for supplying a combustible mixture of fuel and air to said chamber, means providing a variable area of communication between said induction pipe and said combustion chamber and adapted to increase such communication area with increases in altitude, and an aneroid bellows controlling said means.

5. An altitude compensated heater comprising walls forming a combustion chamber, heat exchange means receiving the products of combustion from said combustion chamber, an air induction pipe for said combustion chamber, fuel supply means responsive to differences in pressure between said induction pipe and said combustion chamber and delivering fuel to said induction pipe, and means including an aneroid bellows for preventing increases in said pressure differential with increases in altitude.

6. An altitude compensated heater comprising walls forming a combustion chamber, means including an induction pipe for supplying a combustible mixture of fuel and air to said chamber, variable means located between and controlling communication between said induction pipe and combustion chamber, and means for reducing the flow resistance of said variable means with increases in altitude.

7. An altitude compensated heater comprising walls forming a combustion chamber, a burner tube slidable in one wall thereof, said tube having slots providing communication between the interior of said tube and said combustion chamber and whose free area varies with varying positions of said tube, means for supplying a combustible mixture to the interior of said tube, and means for shifting the position of said burner tube with variations in altitude to increase the free area of said slots with increases in altitude.

8. An altitude compensated heater comprising walls forming a combustion chamber, means including a burner tube slidable in a wall thereof to vary the area of communication between the interior of said tube and said combustion chamber, means responsive to the pressure differential between said combustion chamber and the interior of said burner tube for supplying fuel to said combustion chamber, and an aneroid bellows for varying the position of said burner tube with variations in altitude to increase said communication with increases in altitude.

9. An altitude compensated heater comprising walls forming a combustion chamber, means including a burner tube slidable relative to said combustion chamber to vary the area of communication between said burner tube and the chamber, a casing slidably receiving one end of said burner tube, said end having a radial flange, a bellows connecting said flange to a wall of said casing to form a chamber in free communication with said combustion chamber, said casing having an evacuated chamber of which said flange forms a wall, a spring for urging said burner tube in a direction to expand said evacuated chamber, an induction pipe connected to said burner tube and having an expandible and contractable section, a fuel jet in said induction pipe, a pressure multiplying means for supplying fuel to said jet and having a fuel chamber communicating therewith, said fuel chamber being adapted for connection to a pump or other source of fuel under pressure, a valve for controlling admission of fuel to said fuel chamber, said fuel chamber having an expandible and contractable portion, a movable member for expanding and contracting said por-

tion and for opening said valve upon contraction of said portion, means connecting one side of said movable member with said induction pipe, means for connecting the other side of said movable member with said combustion chamber, a heat exchanger receiving the products of combustion from said combustion chamber, and means for directing ventilating air over said heat exchanger.

10. An altitude compensated heater comprising walls forming a combustion chamber, means including an induction pipe for supplying a combustible mixture to said chamber, means providing a variable area of communication between said pipe and said chamber, means for supplying secondary air to be mixed with the products of combustion leaving said chamber, a heat exchanger for receiving the mixture thus formed, and means for increasing the area of communication between said pipe and chamber and for increasing the velocity of secondary air with increases in altitude.

20 11. An altitude compensated heater comprising walls forming a combustion chamber, means including an induction tube communicating with and supplying combustible mixture to said chamber, said chamber being slidable on said tube to vary the area of communication therebetween, and means responsive to increases in altitude for shifting said combustion chamber on said tube to increase said area.

30 12. An altitude compensated heater comprising walls forming a combustion chamber, means for supplying a combustible mixture thereto, means for supplying secondary air to be mixed with the products of combustion formed in said chamber, and altitude responsive means for shifting said chamber to increase with increases in altitude the velocity of secondary air and to maintain a constant supply of fuel to said chamber.

35 13. An altitude compensated heater comprising walls forming a combustion chamber, means including an induction pipe for supplying a combustible mixture thereto, valve means located between and controlling communication between said pipe and combustion chamber, and an aneroid bellows for increasing the opening of said valve with increases in said altitude.

40 14. An altitude compensated heater comprising walls forming a combustion chamber, means including an induction pipe for supplying a combustible mixture thereto, a conical valve controlling communication between said pipe and chamber, means responsive to pressure differences between said pipe and chamber for delivering fuel to said pipe, an aneroid bellows in said pipe, said valve having a stem connected to said bellows for actuation thereby whereby the degree of opening of said valve is regulated by said barometer to increase said degree with increases in altitude, guide means for said valve stem, said guide means functioning to give a whirling motion to combustible mixture entering said combustion chamber, and a heat exchanger receiving the products of combustion from said combustion chamber.
